PULLEY

Richard K. Whitehead, Sr., Richard K. Whitehead, Jr., and Harry C. Whitehead, all of 1216 Zonolite Road NE, Atlanta, Ga. 30306

Filed Oct. 23, 1968, Ser. No. 14,144

Term of patent 14 years

Int. Cl. D8—03

U.S. Cl. D8—216

Fig. 1

Fig. 2

Fig. 4

Fig. 3

Fig. 4

FIG. 1 is a front view of a pulley embodying our new design;

FIG. 2 is a side view of the pulley shown in FIG. 1, with a portion broken away to show the dished shape of the front;

FIG. 3 is a back view of the pulley shown in FIG. 1; and

FIG. 4 is a perspective view showing the front and one side of the pulley shown in FIG. 1.

The side not shown is the same as the side shown. The broken lines are for illustrative purposes only. We claim:

The ornamental design for a pulley, substantially as shown and described.
